UNITED STATES PATENT OFFICE.

CHARLES M. SORENSEN, OF BROOKLYN, NEW YORK, ASSIGNOR TO VIDAL TYPEWRITER COMPANY, OF NEW YORK, N. Y., A CORPORATION OF CUBA.

TYPE-WRITER-CARRIAGE CONTROL.

No. 880,174.

Specification of Letters Patent.

Patented Feb. 25, 1908.

Application filed October 22, 1907. Serial No. 398,582.

To all whom it may concern:

Be it known that I, CHARLES M. SORENSEN, a citizen of the United States of America, and residing at Brooklyn, in the county of Kings and State of New York, have invented certain new and useful Improvements in Type-Writer-Carriage Controls, of which the following is a specification, such as will enable those skilled in the art to which it appertains

10 to make and use the same.

This invention relates directly to an application for a patent of the United States on typewriters, filed by me on the 22d day of October, 1907, Serial Number 398,580, and 15 has for its object to provide means whereby the carriage of such a machine may be under control at all times; a further object being to provide means for this purpose which are located at the keyboard of the machine; a 20 further object being to provide means at the said keyboard whereby said carriage may be returned to its initial or any intermediate position at any time; a still further object being to provide means at the said keyboard 25 whereby the said carriage may be released from any position and permitted to pass to its extreme or any intermediate position at any time either for tabulating or other purposes and a still further object being to provide such devices which are simple in construction and operation and which are readily adaptable to machines of the present construction.

My invention is fully described in the following specification, of which the accompanying drawings form a part, in which the separate parts thereof are designated by the same reference characters in each of the views, and in which:—

40 Figure 1 is a plan view of a typewriter provided with my invention; and Fig. 2 is a side elevation thereof.

In the drawings forming a part of this application, I have shown a typewriter comprising a support *a*, a carriage *b* movable transversely of said support, a platen *b*² thereon and a keyboard *c* comprising the usual printing, spacing and shifting keys.

Upon the right hand side of the support *a* 45 I have shown a longitudinally arranged bar *d*, provided with a slot *d*², and in which is movable a stud *d*³ of a set of lazy-tong levers *d*⁴ supported and guided by the bar *d* and pivotally connected with the inner lever *d*⁵ 50 is an arm *d*⁵ provided with a transverse

handle or key *d*⁶, this pivotal connection being provided to permit folding the said arm when the typewriter is inclosed in its cover or case and it will be seen that the key *d*⁶, when in position for use, is to the right 60 and in front of the keyboard *c* and at such a distance therefrom as to be in the position of the ball of the hand of an operator on the said keyboard.

Connected with the outer end of the levers *d*⁴ is a cable *e* which is passed around two pulleys *e*² and *e*³ and thence to the other end of the carriage *b* where it is secured and it will be seen that, when the arm *d*⁵ is depressed into its alternate position, the levers 65 *d*⁴ close and the carriage is drawn toward the pulley *e*³ to its full limit and is then in its initial position for beginning a new line of writing or, if desired, said carriage may be drawn to any intermediate position for tabulating or any other purpose and, in the process 70 of writing, said carriage passes again toward the left of the machine by the tension always provided for this purpose.

At the left of the keyboard *c* is shown a 75 key *f* which is connected with a trip *f*² by means of a rod *f*³, said trip bearing normally upon a lock *h* normally engaging a rack *h*² secured to the carriage *b* and at *i* is shown a finger which is operated, either by the space 80 key or any of the printing keys, toward the said rack and therethrough and forcing the lock *h* out of engagement with the said rack whereby the spacing between letters or words is accomplished and, if the key *f* be drawn 85 toward the operator, said lock *h* is again released from the rack and, the finger *i* not being in engagement with the rack at this time, the carriage is free to pass to its limit of movement or to a position where the lock 90 *h* is again operative through the release of the key *f*, and thus the carriage may be controlled 95 for tabulating or other purposes in its movement toward the left and by the key *d*⁶ moving it toward the right.

100 Various methods other than the lazy-tong levers shown and described may be used to accomplish the desired result and other changes in and modifications of the carriage control may be made without departing from 105 the spirit of this invention or sacrificing its advantages and, with this reservation,

What I claim as new and desire to secure by Letters Patent, is:—

1. In combination with the carriage of a 110

typewriter and the platen thereof, a longitudinal bar at one end of the typewriter frame having a slot along its length, a set of lazy tong levers arranged at one side of said bar, a stud carried by said levers and operating in said slot, and a flexible connection connected to said levers and to the opposite end of the carriage.

- 5 2. In combination with the carriage of a typewriter and the platen thereof, a longitudinal bar at one end of the typewriter frame having a slot along its length, a set of lazy tong levers arranged at one side of said bar, a stud carried by said levers and operating in said slot, a pulley at the end of said bar, a second pulley at right angles to said first pulley, and a cable connected to said levers engaging over both of said pulleys and connected to said carriage.
- 10 3. In combination with the carriage of a typewriter, a longitudinal bar slotted at one end and carrying a pulley at its other end, a set of lazy tong levers arranged at one side of said bar and carrying a stud which operates in said slot, said levers being pivoted to the front end of said bar at a relatively fixed
- 15
- 20
- 25

point thereon, an arm connected to the foremost of said levers, an inwardly extending transverse handle secured to said arm, and a cable connected to the outermost of said levers passing over said pulley and secured to said carriage.

4. In combination with the carriage of a typewriter, a set of lazy tong levers arranged at right angles to said carriage, an operating arm connected to the foremost of said levers, a pulley at the rear end of said levers, a cable connected to the rear of said levers and to the carriage and passing over said pulley, means for conducting said cable from said pulley to said carriage, a projection carried by said levers and means for receiving and guiding said projection during the movement of said levers.

In testimony that I claim the foregoing as my invention I have signed my name in presence of the subscribing witnesses this 21st day of October, 1907.

CHARLES M. SORENSEN.
